(57) **CLAIM**

The ornamental design for a skin analyzer as shown and described.

DESCRIPTION

FIG. 1. is a front view of a skin analyzer according to the present invention.

FIG. 2 is a rear view of the skin analyzer according to the present invention.

FIG. 3 is a perspective of the skin analyzer according to the present invention.

FIG. 4 is a top view of the skin analyzer according to the present invention.

FIG. 5 is a bottom view of the skin analyzer according to the present invention.

FIG. 6 is a left-side view of the skin analyzer according to the present invention; and,

FIG. 7 is a right-side view of the skin analyzer according to the present invention.

The broken lines in the drawings illustrate portions of the skin analyzer that form no part of the claimed design.

1 Claim, 7 Drawing Sheets
